J. F. RUTH.

WINDOW.

APPLICATION FILED MAR. 24, 1913.

1,254,280.

Patented Jan. 22, 1918.

UNITED STATES PATENT OFFICE.

JOHN F. RUTH, OF ST. LOUIS, MISSOURI.

WINDOW.

1,254,280.

Specification of Letters Patent. Patented Jan. 22, 1918.

Application filed March 24, 1913. Serial No. 756,556.

To all whom it may concern:

Be it known that I, JOHN F. RUTH, a citizen of the United States, and resident of St. Louis, Missouri, have invented certain new and useful Improvements in Windows, of which the following is a specification containing a full, clear, and exact description, reference being had to the accompanying drawings, forming a part hereof.

10 My invention relates to improvements in windows, and more particularly relates to that class of windows in which the sash is constructed wholly of metal and the glass therein is provided with a metal reinforce.

15 The object of my invention is to construct a sash in which there is placed clamping devices arranged to be secured to the margins of the glass in such manner that the glass may have a limited degree of freedom to 20 move relative to the sash, yet be held so that its margins may not be withdrawn from the grooves in the sash.

A further and more specific object of my 25 invention is to construct an improved form of clamp whose shape and construction permit it to be secured to glass and to adhere thereto by pressure without producing torsional or lateral strains upon the glass which would tend to break or shatter the glass.

30 With the above purposes in view my invention consists in certain novel features of the construction and arrangement of parts as will be hereinafter described, pointed out in the claims and illustrated by the accompanying drawings, in which—

Figure 1 is a face view of a sash constructed according to my invention, a portion thereof being shown in section;

Fig. 2 is a transverse sectional elevation 40 of my improved sash showing the arrangement of the glass securing devices;

Fig. 3 is an outside fragmental elevation 45 of the lower rail and glass, a portion of the lower rail being broken away to reveal the clamp;

Fig. 4 is a sectional plan taken on the line 4—4 of Fig. 2; and

Fig. 5 is an elevation of one of my improved clamps.

50 Referring by numerals to the accompanying drawings:

6—6 designates the stiles, 7 the upper rail and 8 the lower rail of my improved sash, all of which are united in a common manner 55 to form a substantially rectangular frame.

Three of the members just described are or

may be of similar construction and any cross section of which presents a groove 9 to receive the edge of the glass 10 and a hollow body surrounding the groove. 60

The fourth member has a cross section whose appearance is substantially the same as the cross section of either of the other three members and contains a slot 11 instead of a groove such as 9 and a removable wall 65 12, which permits of the insertion of the glass through the slot 11 to a position seated in the grooves of the three remaining sash members.

This much of my sash forms no part of 70 my invention and any well known construction of sheet metal sash may be employed, the only essential to the sash being grooves for holding the glass in place, and hollow bodies surrounding the groove in order to 75 provide for the reception of my improved clamping devices.

My improved clamping device in itself comprises a pair of relatively movable jaws 13 and 14, integral angular extensions 15 and 80 16 and a set screw 17 carried by one extension and arranged to bear on the other extension for the movement of the jaws.

Each jaw and its extension is preferably constructed from a single piece of material, 85 the one jaw having formed in opposing side margins the depressions 18, and the other jaw being provided with spaced apart tines 19 which are arranged to embrace the material of the opposite jaw between the depressions 18 and are then bent to hold the two jaws together. 90

Adjacent the free end of each of the jaws there is a flat face 20 which serves the double function of providing a comparatively broad 95 face for adhesion to the glass and also holds the two jaws in a fixed relation with the glass.

From these relatively broad faces the bodies of the jaws incline in directions away 100 from the glass so that, in case the body of the glass is bent out of shape, the margins thereof will be free to yield.

Formed in one of the jaws of each clamp there is a slot or opening 21 and struck from 105 the wall of the glass receiving groove there is a lip 22 the end of which is arranged to be inserted through the slot or opening in the jaw and upset to provide a means whereby the clamp may be secured to the sash. 110

Formed in the sash adjacent each of the clamps there is an opening 23 which pro-

vides for the insertion of the clamp into the sash and the insertion of a tool for the turning of the set screws carried by the clamps.

By this arrangement a sash may be furnished fully equipped with glass securing clamps which permit of the glazing of the sash without the employment of tools other than one to draw up the set screws.

When a window sash is equipped with my improved clamps secured to the margin of a sheet of glass having a metallic reinforce the dangers and annoyances incident to broken and falling glass are almost entirely obviated.

15 A further and more important advantage arising from the use of my improved clamps on reinforced glass is that, in case of fire causing the glass to be heated and bulged to an extent tending to withdraw the margins of the glass from the grooves in the sash, my clamps limit the extent of the withdrawal and prevent a complete withdrawal.

I claim:

1. In combination with a hollow metallic sash having grooves to receive the margins of a sheet of glass and a sheet of glass having a wire mesh reinforce embedded therein and co-extensive only with the sheet of glass, a plurality of securing means engageable with the walls of said grooves in the sash and arranged to embrace said walls of the groove and a device at each securing means for creating added pressure to the walls of said grooves whereby to create such clamping pressures at the margins of the sheet of glass which will secure the wire mesh to the walls of the grooves in the sash so that in the event the body of the sheet of glass is broken the glass will be prevented from falling by reason of the wire mesh being secured in the sash.

2. In combination with a sheet of glass having a reinforce embedded therein and a sash arranged to surround the margins of the sheet of glass, a glass securing means

and a device at the securing means whereby to create such clamping pressure to at least one margin of the sheet of glass which will secure the reinforce to the sash so that the sheet of glass will be prevented from loosening or falling by reason of the reinforce being secured to the sash.

3. In combination with a hollow metallic sash having spaced walls, a sheet of reinforced glass having its margins arranged within said walls, portions of said walls being removed and variable pressure clamping devices directly engageable with the sheet of glass at the points of removal of portions of said walls and surrounding at least portions of said walls whereby the means for securing the glass to the sash will permit of certain glass flexure to the sash without danger of breakage and whereby the margins of the sheet of glass may be clamped with such pressure as to secure the reinforce against removal from the sash in order to prevent falling glass in the event the sheet is broken.

4. In combination with a sash and a sheet of glass having a reinforce, a glass securing means, comprising a variable tension device, secured to the sash and arranged to clamp, at least one margin of the sheet of glass to the sash in such manner as to produce a pressure on the glass, sufficient to secure the reinforce to the sash, so that even though the body of the sheet of glass be fused by fire or broken by impact at a point or points other than the point of securing, the reinforce will be maintained in its secured position, in the sash and the glass held against dislodgment from the sash.

In testimony whereof, I have signed my name to this specification, in presence of two subscribing witnesses.

JOHN F. RUTH.

Witnesses:

E. L. WALLACE,

N. G. BUTLER.
